UNITED STATES PATENT OFFICE.

CORNELIUS S. MORRIS, OF MOLINE, ILLINOIS.

TOY.

SPECIFICATION forming part of Letters Patent No. 448,539, dated March 17, 1891.

Application filed December 26, 1890. Serial No. 375,832. (No model.)

To all whom it may concern:

Be it known that I, CORNELIUS S. MORRIS, a citizen of the United States, residing at Moline, in the county of Rock Island and State 5 of Illinois, have invented certain new and useful Improvements in Toys; and I do hereby declare the following to be a full, clear, and exact description of the invention, such as will enable others skilled in the art to which it applies to make and use the same.

This invention is designed to furnish an amusing and attractive toy for children, by means of which a party may be able to select any of a number of articles, as more fully 15 hereinafter explained.

In the accompanying drawings, making part of this specification, Figure 1 represents a front view of my improved device. Fig. 2 represents a vertical sectional view thereof, 20 taken in a plane at a right angle to the wheel of the device; and Fig. 3 is a horizontal sectional view taken in a plane passing through the axis of said wheel.

Referring to the drawings, the letter A indicates a casing mounted upon a suitable base B. The lower part of said casing is rectangular in shape and is provided with a drawer C, which is provided with a locking or fastening device E of any suitable description. Above the lower portion containing the 25 drawer the casing is enlarged or widened, and in said enlarged portion is located a wheel G, which is mounted upon a shaft H, journaled in bearing in the front of the casing and a bracket I at the rear of the casing in the interior thereof. The front of the casing is provided with a circular dial or index plate K, having at equidistant intervals spaces L, in which are inscribed the character or names 30 of the articles to be selected, such as "top," "ball," &c. The front journal of the wheel-shaft projects beyond its bearing, which is at the center of the dial or index plate, and at its projecting end is provided with an index 35 finger or pointer M, for the purpose herein-after explained. The wheel consists of an annulus N, preferably of sheet metal, mounted at the outer ends of a series of spokes P, extending radially from the shaft or axle K of 40 the said wheel. At equidistant points on the periphery of the wheel are located inclined

buckets or shelves, for the purpose herein-after explained.

The letter S indicates a segmental guard or guide, which extends over the upper quarter 55 of the wheel at one side, as shown in Fig. 2 of the drawings. The upper portion of the casing is contracted, the sides being brought toward each other. Directly over the axial line of the wheel-shaft and at the top the casing is provided with a slot for the insertion of a disk of metal or other material of sufficient weight to overbalance the wheel and cause it to turn, the buckets or shelves being set at such an angle as to receive said disk 60 and turn the disk in one direction invariably.

The most convenient manner of operating the device will be by means of a coin of any suitable denomination, and the size of the slot at the top of the casing may be made to 7c admit a coin of any predetermined size or denomination.

The operation of my invention will be readily understood from the above description, and it is as follows: When a disk or coin is 75 dropped through the upper slot in the upper part of the casing, it falls into one of the buckets, overbalances the wheel, and causes it to rotate, the buckets passing between the segmental guards or guides until the disk or coin 80 is discharged into the drawer below. The momentum given the wheel by the disk or coin will cause it to revolve after the disk or coin has been discharged into the box for a limited time, and when the wheel finally comes to a 85 rest the index finger or pointer will rest with its pointing extremity opposite the character indicating the article automatically selected.

The articles to be distributed may be suitably arranged and characterized by means of 90 characters corresponding to those on the dial-plate.

The characters on the character-spaces may be changed as may be desired.

Having thus described my invention, what 95 I claim, and desire to secure by Letters Patent, is—

A toy consisting of a casing having a dial-plate at its front, provided with character-spaces at equidistant intervals, a receptacle 100 near its base, a wheel above provided with inclined buckets or shelves on its periphery,

and a shaft having its forward journal projecting through its bearing at the center of the dial-plate and provided with an index finger or pointer, the casing at its top having 5 a slot through which a disk or coin may be inserted, so as to rotate the wheel and be deposited thereby in the receptacle after giving the wheel a varying momentum, which will cause the pointer or index finger to rest at a

previously-undetermined point on the dial-plate, substantially as specified.

In testimony whereof I affix my signature in presence of two witnesses.

CORNELIUS S. MORRIS.
